UNITED STATES PATENT OFFICE.

HENRY ABBOTT, OF NEWARK, NEW JERSEY, ASSIGNOR OF THREE-FOURTHS
TO WINTON C. GARRISON, OF SAME PLACE, AND THE ELGIN NATIONAL
WATCH COMPANY, OF CHICAGO, ILLINOIS.

ORNAMENTING ENAMELED OR GLAZED SURFACES.

SPECIFICATION forming part of Letters Patent No. 309,910, dated December 30, 1884.

Application filed December 5, 1883. (Specimens.)

To all whom it may concern:

Be it known that I, HENRY ABBOTT, of Newark, in the county of Essex, and in the State of New Jersey, have invented certain new and useful Improvements in Ornamenting Enameled or Glazed Surfaces; and I do hereby declare that the following is a full, clear, and exact description thereof.

My invention relates to certain improvements in the method of ornamenting enameled or glazed surfaces, heretofore made by me, in which vitrifiable colors are filled into the sunk portions of engraved or etched plates, and fluid collodion then flowed over the surface of the plate and caused to permeate and become incorporated with said colors, which collodion, after hardening, is removed in the form of a film having upon its face the design in color. The film thus produced is afterward used as a transfer medium for said design to the surface of the article to be ornamented, when by the application of heat the vitrifiable color becomes incorporated with such surface.

In the carrying out of my said method the 25 vitrifiable color has been applied to the plate in the manner usual in plate-printing—that is, by means of a pad or the hand of the operator; but the result has not always been satisfactory, as the lines, more especially the heavy 30 lines, would sometimes be imperfectly filled, and the colored enamel, when burned in, present a lumpy appearance, with ragged edges of some of its lines.

To obviate this defect and to insure full 35 sharp lines in the completed design when transferred is the object of my present invention, which consists, principally, in the method employed for producing transfer-films, substantially as hereinafter specified.

It consists, further, in the plate employed 40 for receiving and containing the colored material, substantially as and for the purpose hereinafter shown.

In the carrying into effect my invention a 45 plate, preferably copper, has engraved or etched within its surface the desired design, care being had that the heavy lines have substantially uniform depths, and that their bottoms are flat and smooth. Over the prepared 50 surface of the plate thus formed is evenly spread a coat of colored paint having for its body any of the vitrifiable materials such as are used in encaustic painting, and after the

same has dried such as adheres to the surface is removed, leaving the lines or sunk portions 55 filled with said colored material of a uniform thickness. The plate is now placed in a horizontal position and liquid collodion flowed over its face and caused to permeate and become incorporated with the colored material 60 within the sunk portions, after which said collodion is permitted to harden, and is then removed from the plate, taking with it the colored design.

It is found that by my method each portion 65 of the design is perfectly formed, and when transferred to and burned into the surface of the article to be ornamented such design has all of the sharpness and fidelity of the original 70 engraving.

While the plate having flat bottoms of its heavy lines is preferably employed, my method of filling in the color may be satisfactorily used upon plates engraved in the usual manner.

Having thus fully set forth the nature and 75 merits of my invention, what I claim as new is—

1. The method of producing transfer-films, consisting, first, in filling the lines and coating the surface of an engraved or etched plate with liquid colored material, and permitting the same to dry, then removing the colored material from the surface of said plate, leaving its lines filled, then flowing over said surface liquid collodion, and causing the same to permeate and become incorporated with said colored material, and, lastly, permitting said collodion to harden, and then removing the same, with its adhering or incorporated 85 design, in the form of a film, substantially as specified.

2. As a means for producing transfer-films, a plate having engraved, etched, or otherwise formed in intaglio within its surface a design 95 the heavy lines of which have flat smooth bottoms, substantially as and for the purpose shown.

In testimony that I claim the foregoing I have hereunto set my hand this 4th day of December, A. D. 1883.

HENRY ABBOTT.
